UNITED STATES PATENT OFFICE

104,763

DESIGN FOR A HEATER REGISTER OR SIMILAR ARTICLE

Rowland J. Black, Buffalo, N. Y.

Application April 5, 1937, Serial No. 68,561

Term of patent 7 years

To all whom it may concern:

Be it known that I, Rowland J. Black, a citizen of the United States and a resident of the city of Buffalo, in the county of Erie and State of New York, have invented a new, original, and ornamental Design for a Heater Register or Similar Article, of which the following is a specification, reference being had to the accompanying drawing, forming a part thereof.

On the drawing:

Figure 1 is a top plan view of a heater register or similar article, showing my new design; and Figure 2 is a side elevational view thereof.

I claim:

The ornamental design for a heater register or similar article as shown.

ROWLAND J. BLACK.
